Samuel J. Smith, of New York, N. Y.
Letters Patent No 1249, dated June 12, 1860.

The schedule referred to in these Letters Patent, and making part of the same.

To all whom it may concern.

Be it known that S. S. J. Smith, of the City, County and State of New York, have invented or produced a new and original design for a Nut Cracker, and I do hereby declare that the following is a full, clear and exact description thereof, reference being had to the accompanying drawings, making a part of this specification, in which

Figure 1, represents a side view of the design for a Nut Cracker.

the opposite side being precisely alike.

Figure 1. is a top view of figure 1.

Similar letters of reference indicate corresponding parts in both figures.

This invention is intended for cracking nuts, and it consists in giving to the machine the shape of a bird's head, with a portion projecting out from the back of the head that is used as a lever for operating the lower jaw of the bird, between which, and the upper jaw, or beak, the nuts are cracked, the whole to be shaped and ornamented, as will be seen from the following description, and accompany drawings.

In the drawings, A, represents the head of a bird, an eagle's head will be preferable - with the upper bill a, curved as shown in figure 1. and the lower bill b, capable of opening or closing. The head and neck portion B, should be ornamented with plumage as shown in the drawings. From the back of the head A, proceeds out at any suitable angle, a curved arm C, that may be shaped like a feather.

The whole will be made of cast metal, and painted to suit the fancy, and screwed down to a stand D, or to a bench or table and when finished, will present a very neat and elegant appearance, and serve for a convenient nut cracker.

What I claim as new, and desire to secure by Letters Patent, is -

The bird's head A, with a feather C, projecting out from the back of the head as represented, and for the purposes set forth.

End Witnesses.
